UNITED STATES PATENT OFFICE

2,113,721

DRAIN TRAP

Charles Vance Dame, Lanark, Ill.

Application July 17, 1937, Serial No. 154,136

8 Claims. (Cl. 182—7)

This invention relates to improvements in drain traps.

One object of the invention is to provide a drain trap having fluid retaining portions so shaped or so expansible or flexible as to prevent cracking in case of freezing of the trapping fluid therein.

Another object of the invention is to provide an improved trap which can be installed concentrically in a drain line whereby the trap without disassembly can be freed of accumulated deposits by means of a suitable rotary tool of the type disclosed in my United States Patent No. 2,074,462, granted March 23, 1937.

Another object of the invention is to provide a drain trap having a relatively great fluid holding capacity which provides adequate trapping or sealing action during protracted periods of non-use of the drain system with which the same is installed.

Other objects and advantages of the present improvements will be apparent from a consideration of the following specification and accompanying drawing, in which:

Fig. 1 is a vertical sectional view of a drain trap embodying the present improvements;

Fig. 2 is a broken top plan view of the drain trap; and

Fig. 3 is a broken perspective view of a flexible supporting means for a water retaining receptacle forming a portion of the trapping means.

In the drawing, 10 is an outer casing which may be of reduced diameter at its lower end and threaded as at 11 for connection in a drain line. The upper end of the casing 10 is provided with a cover 12 which may be threaded as at 13 to the casing and provided with a threaded nipple 14 within which may be screwed a nipple 15 which is carried by an upper wall 16 of an inverted frusto-conical receptacle 17. The inner wall of the nipple 15 may likewise be threaded for receiving an intake pipe 18 of the drain line.

The wall 15 preferably is of flexible non-rusting material while the wall 17 is inclined at such angle that fracture or breakage of the same will not occur in case water or other fluid freezes or solidifies therein. The wall 16 may be brazed or soldered or welded as at 19 to the upper edge of the wall 17 or the two walls may be integral if desired as when made of spun metal, for example. At the lower end of the receptacle 17 is an outlet opening 20 which is concentric with the pipe 18.

Secured to or at the margin of the opening 18 is a transverse member 21 which terminates in

an upstanding wall 22 which may be vertical, if desired, as shown in the drawing. The wall 22 preferably is fluted or corrugated as shown at 23 to increase its expansibility or flexibility. The upper end of the wall 22 may have a downwardly turned flange 24 which contacts the outer surface of the receptacle 17 and may be welded or soldered thereto if desired or it may be unattached.

In the form of the invention shown in the drawing, the member 21 including its upstanding wall 22 provides in cooperation with the wall 17 a chamber 25 which, if desired, may be filled with suitable packing to exclude the water in the event the flange 24 is not hermetically sealed to the wall 17. This packing may be of heat insulating characteristics if desired.

Surrounding the member 21 is a cup-shaped receptacle indicated generally by the numeral 26 having a transverse bottom wall 27 and an upstanding side wall 28 which also preferably is corrugated or fluted to provide for radial expansibility. The bottom wall 27 is provided with a central elevation or dome 29 within which, on the lower side thereof, is seated bowed portions 30 of a flexible cruciform member indicated generally by the numeral 31. The member 31 has arms 32 which extend radially of the casing and which may terminate in angular ends 33 which seat against the tapered wall of the lower portion of the casing 10 as shown clearly in Fig. 1. The arms 32 may likewise be provided adjacent the bowed portions 30 with upwardly directed portions 34 which contact the wall 27 for supporting the receptacle 26 against tilting action.

It will be noted that the upstanding walls 28 of the receptacle 26 are annularly spaced from the interior of the casing 10 and that the upper end of the receptacle 26 is at an elevation lower than the wall 16 and determines the level of the trapping fluid within the trap. Fluid entering the trap by means of the pipe 18 flows into the receptacle 17 through the opening 20 in the bottom thereof and radially through the passage 35 formed by the spaced transverse wall of member 21 and the bottom wall 27 of receptacle 26 and may rise into the chamber 36 formed by the upstanding walls 22 and 28. When the fluid level reaches the level of the upper end of wall 28, the fluid will overflow through the annular chamber 37 formed between the wall 28 and the wall of the casing 10 and be discharged through the lower end of the trap into the drain system.

The wall 16, as stated, preferably is flexible so that such wall may bulge upwardly in the event pressure is exerted thereagainst by the freezing

fluid although the vertical distance between the wall 16 and the water level is sufficient to preclude the exertion of pressure against the wall 16 by the freezing of water, for example, within 5 the chamber 17. Should liquid freeze in the chamber 35, the pressure exerted upon the expansion thereof will depress the flexible wall 27 due to its inherent flexibility and also due to the fact that it rests upon the flexible member 31. 10 The freezing of liquid within the chamber 36 may effect inward movement of the corrugated wall 22 and radial outward movement of the corrugated wall 28, thus preventing cracking of the metal of which the parts are made. By the improved construction, it will be seen that both 15 outward or lateral expansibility and vertical displacement of the parts are provided to prevent fracture of the fluid holding portions of the trap in case of freezing.

20 In assembling the trap, the cover may be screwed upon the nipple 15 which provides a unitary construction as between the cover, the wall 17 and the receptacle including the member 21. Thereafter, the cover and supported 25 parts may be screwed upon the casing 10, after which the pipe 18 may be screwed into the nipple 15 and the discharge pipe (not shown) may be screwed onto the threaded portion 16 in connecting the trap in the drain line. Where the 30 trap is connected in a drain line leading from a sink, for example, it may be cleaned readily of accumulated matter within the chambers 35 and 36 by means of a rotary tool inserted downwardly through the pipe 18 and provided with flexible 35 arms of the type shown in my above mentioned patent. The arms will be deflected readily by the dome 29 through or into the passages 35 and 36 whereupon rotation of the tool will free the walls of such accumulated matter.

40 While I have shown and described an embodiment of my improvements for the purpose of illustration, I do not wish to be restricted specifically thereto except as so limited by the appended claims.

45 I claim:

1. A drain trap comprising an outer casing adapted to be connected in a drain line, and trapping means in said casing comprising a central receptacle having outwardly flaring side walls and means providing an annular passage 50 open at the upper end and communicating at the lower end with said central receptacle and provided with an expansible wall.
2. A drain trap comprising an outer casing 55 adapted to be connected in a drain line, and trapping means therein comprising a central fluid retaining chamber and a communicating annular fluid retaining chamber provided with an outwardly expansible wall.
3. A drain trap comprising an outer casing 60 adapted to be connected in a drain line, and trapping means in said casing, said means comprising a central chamber, an annular chamber spaced from the walls of said casing and surrounding said central chamber and providing an overflow at the upper end and a transversely

disposed chamber providing communication between the lower end of said annular chamber and the lower end of said central chamber, said transversely disposed chamber having a flexible lower wall adapted to be flexed outwardly by the expanding action exerted thereon by liquid freezing within the trap. 5

4. A drain trap comprising a casing adapted to be connected in a drain line, a fluid retaining means in said casing comprising a longitudinally 10 disposed chamber, a transverse chamber centrally communicating with the lower end of said longitudinal chamber, and an annular upright chamber communicating with the outer portion of said transverse chamber, said upright chamber having flexible side walls spaced from said longitudinal chamber and from said casing and providing an overflow at the upper end thereof. 15

5. A drain trap comprising an outer casing 20 provided with an inlet and outlet for connection in a drain line, a central fluid chamber having outwardly flaring walls, and spaced flexible walls defining therebetween a transverse chamber communicating with the lower end of said central chamber and an annular chamber communicating 25 with said transverse chamber and providing an overflow at the upper end spaced from said casing.

6. A drain trap comprising an outer casing having an outlet at the lower end and a removable cover provided with a fluid intake, a fluid retaining receptacle open at the upper end and positioned in said casing and spaced annularly from the inner wall thereof, a second receptacle open at the lower end and supported by said 30 cover within said first receptacle in spaced relation with respect to the walls of the latter to provide an annular overflow chamber in said first receptacle communicating with the lower end of the second receptacle, and flexible means 35 for supporting said first mentioned receptacle within said casing to provide for relative movement of said receptacle when subjected to the expanding action of liquid freezing therein. 40

7. A drain trap comprising an outer casing 45 having an outlet at the lower end and a removable cover provided with a fluid intake, a fluid retaining receptacle open at the upper end and having an outwardly expansible side wall positioned in said casing and spaced annularly from the inner wall thereof, flexible means for supporting said receptacle in said casing, and a second receptacle open at the lower end and supported by said cover within said first receptacle in spaced relation with respect to the walls of the 50 latter to provide an annular overflow chamber in the first receptacle communicating with the lower end of said second receptacle. 55

8. A drain trap comprising an outer casing, a receptacle in said casing provided with readily expansible side walls, a second receptacle positioned in said first receptacle and communicating therewith to provide fluid retaining means, and a flexible mounting means for said first receptacle to accommodate vertical movement of the same. 60

CHARLES VANCE DAME.
